UNITED STATES PATENT OFFICE.

PAUL AUGUSTE HELMBOLD, OF VOHWINKEL, GERMANY.

DRIVING MECHANISM FOR THE COMB CYLINDERS OF ROTARY COMBING MACHINES.

Application filed December 6, 1920. Serial No. 428,531.

To all whom it may concern:

Be it known that I, PAUL AUGUSTE HELMBOLD, a citizen of the French Republic, residing at Vohwinkel, Rhineland, Germany, have invented a new and useful Improvement in Driving Mechanism for the Comb Cylinders of Rotary Combing Machines, of which the following is a specification.

This invention consists in an improved driving arrangement for the comb cylinder or rotary combing machines of the type having swinging nippers which remain stationary or almost stationary during the time the comb is in action.

15 In accordance with the present invention the comb cylinder receives a variable speed in such a manner that it is rotated more slowly in correspondence with the increasing resistance which the more closely positioned 20 needles of the successive comb shafts of the comb segment find in the tufts of fibres, and makes up for the lost time as soon as the comb segment has no further work to do. This enables a substantially higher production 25 of the combing machine to be obtained. If for example the peripheral speed of the comb segment is reduced by five per cent during the time the fine needles are in action and on the other hand the peripheral 30 speed during the time that the needles are not working is increased by only fifteen percent, an average of five per cent higher speed of the comb cylinder is obtained and consequently the production of the machine is increased by five per cent.

Further advantages of the invention are that smoother combing of the tufts of fibres by the closely-positioned needles takes place; that the fine rows of needles are subjected to less tear and wear; and that finally a by-product is obtained which contains fewer torn fibres than when the comb cylinder is driven in the hitherto usual manner.

45 In the accompanying drawing I have illustrated two suitable constructions of driving mechanism, but I make no claim to that mechanism per se as similar mechanism for imparting a variable speed from one shaft to another is well known and has been employed to impart a variable speed to a comb cylinder for a different purpose from mine. My invention consists in the particular manner in which the variable motion is imparted so that the aforesaid higher production and advantages are obtained.

Figs. 1 and 2 show one of the said constructions; and

Figs 3 and 4 the other.

Fig. 5 is a diagrammatic view showing 60 the position of the cylinder comb at the time that the peripheral speed thereof is reduced.

Fig. 6 illustrates the position of the parts at the time that the speed thereof is increased.

Inasmuch as the invention relates simply to the mechanism for controlling the speed of the comb cylinder at different points in its rotative movement and for a particular 70 purpose I have not thought it necessary to illustrate herein a combing machine but have indicated diagrammatically in Figs. 5 and 6 the comb cylinder at *n* having teeth *t* on a portion of its periphery and have indicated at *p* the nippers which hold the lap *s* while the fringe *u* is being combed. *V* indicate the usual detaching rollers. These parts are or may be all of usual construction and operate in the usual manner, it being understood that the needles *t* are so arranged that those in the front row are coarser and more widely spaced than the needles in the succeeding row, the needles in the last row being finest and closest together.

As stated above the present invention relates to means operating to retard the rotative movement of the comb cylinder while the fine needles are acting on the fringe *u* 90 as shown in Fig. 5 and to increase the speed of the comb cylinder when the needles are not working as shown in Fig. 6.

The comb cylinder *1* is mounted on a shaft *a* and in the construction shown in Figs. 1 and 2 this shaft has loosely mounted on it a toothed wheel *c*, said wheel being rotated in the direction of the arrow at a uniform speed from the shaft *b*, the latter having a gear *3* thereon which meshes with and drives the toothed wheel *c*. In said toothed wheel *c* two studs *d* are fixed at one side at diametrically opposite points, upon which toothed wheels *e* together with eccentrics *f* formed in one piece therewith are rotatably mounted. The rods *g* of these eccentrics engage lever arms *h* which are keyed on the comb cylinder shaft *a*. The toothed wheels *e* are in engagement with a stationary toothed wheel *i* arranged in the machine.

In this construction the rotation of the toothed wheel *c* is transferred to the comb

cylinder shaft through the eccentrics *f* and the rods *g*, *h*, and a fixed alteration of speed of the same is brought about through the simultaneous rotation of the eccentrics *f* caused by the rolling of the wheels *e* upon the wheel *i*.

In the construction of the new driving device shown in Figs. 3 and 4 a predetermined variation of speed of the comb cylinder shaft *a* is obtained by interposing between it and the driving shaft *b* a transmission mechanism consisting of eccentric wheels *k*, *l*, the movement of which is transmitted through the pair of toothed wheels *m*, *j* to the comb cylinder shaft *a* and thereby to the comb cylinder itself.

The mechanism for varying the speed of the comb cylinder shaft *a* is so arranged and timed with relation to the action of the comb cylinder and the nippers that the reduction in speed commences after the coarse needles have entered the fringe *u* and before the fine needles come into action and with this invention, therefore, the speed of the comb cylinder is reduced while the fine needles are in action, the position of the parts at this time being indicated in Fig. 5. After the comb cylinder has been rotated far enough to carry the fine needles clear of the work and the parts are in the position shown in Fig. 6, then the speed of the shaft *a* and the comb cylinder is accelerated to more than make up for the reduction of the speed when the parts are in the position shown in Fig. 5.

With this construction it is possible to slow down the speed while the fine needles are acting thus subjecting them to less wear

and tear and producing a better product and at the same time to increase the production because when the needles are out of the work the comb cylinder may be speeded up sufficiently to more than make up for the loss of speed during the combing with the fine needles.

What I claim is:

1. In a rotary combing machine of the type having swinging nippers which remain practically stationary during the time the comb is in action, the employment of means for imparting a variable speed to the comb cylinder from a uniformly rotating shaft in such a manner that in each revolution the said cylinder is rotated more and more slowly as the resistance to the successive rows of needles increases and the lost time is made up by an acceleration of the speed as soon as the needles are clear of the work, substantially as described and for the purpose set forth.

2. In a rotary combing machine of the type having swinging nippers which remain practically stationary during the time the comb is in action and in which the comb cylinder has a plurality of rows of needles with the needles in the last rows positioned more closely together than those in the first rows, the combination with a shaft on which the comb cylinder is mounted, of a driving shaft rotating at a uniform speed, and variable speed mechanism operatively connecting said shaft and causing the comb cylinder shaft to have a reduced speed while the more-closely positioned needles are in action, and an accelerated speed while the needles are clear of the work.

PAUL AUGUSTE HELMBOLD.
